UNITED STATES PATENT OFFICE

98,777

DESIGN FOR AN IGNITION COIL

Fred A. Oberheu, Detroit, Mich., assignor to General Motors Corporation, Detroit, Mich., a corporation of Delaware

Application January 8, 1936, Serial No. 60,473

Term of patent 7 years

To all whom it may concern:

Be it known that I, Fred A. Oberheu, a citizen of the United States, residing at Detroit, in the county of Wayne and State of Michigan, have invented a new, original, and ornamental Design for Ignition Coils, of which the following is a specification, reference being had to the accompanying drawing, forming part thereof.

In the drawing, the figure is a perspective view of the ignition coil.

I claim:

The ornamental design for an ignition coil substantially as shown.

F. A. OBERHEU.
